UNITED STATES PATENT OFFICE.

JOSIAH LEDAN, OF HANNIBAL, MISSOURI.

WASHBOARD.

1,250,193.

Specification of Letters Patent. Patented Dec. 18, 1917.

Application filed August 15, 1917. Serial No. 186,385.

To all whom it may concern:

Be it known that I, JOSIAH LEDAN, a citizen of the United States, residing at Hannibal, in the county of Marion and State of Missouri, have invented certain new and useful Improvements in Washboards, of which the following is a specification.

This invention relates to wash boards.

One of the main objects of the invention is to provide a board the corrugated rubbing surface of which is entirely of wood construction thus eliminating injury to the hands of the user, and tearing of the clothing being washed such as often occurs where a metal rubbing surface is used and has become partly worn away. A still further object is to provide a board having a removable back for the rubbing portion of the board which may be quickly and easily removed to permit thorough cleaning and washing of the rubbing elements. A still further object is to provide a board composed of a minimum of parts, the parts being of standard construction and so related as to permit the board to be produced in a very short time and at comparatively small cost. Further objects will appear from the detailed description.

In the drawings:

Fig. 1 is a front view of a board constructed in accordance with my invention partly broken away to show the interior construction.

Fig. 2 is a side view of the same.

Fig. 3 is a back view.

Fig. 4 is a section taken substantially on line 4—4 of Fig. 3.

Fig. 5 is a section taken on line 5—5 of Fig. 4.

The side pieces 1 and 2 of the board are of substantially elongated elliptical or cigar shape, being tapered at their lower ends to provide the supporting legs 3 and 4, respectively. Side piece 2 is provided, in its inner face, with a central longitudinally extending groove 5, which is in alignment transversely of the board with a similar groove 6 formed in the inner face of side piece 1. A bar 7 extends across the board a short distance from the lower ends of the side pieces 1 and 2. The ends of this bar extend through the side pieces, and the bar is fixedly secured in position at the lower ends of the grooves 5 and 6 by means of securing screws 8. A plurality of rubbing members or rods

9 are mounted on the lower bar 7 in superposed relation, the end portions of these rods fitting snugly into the grooves 5 and 6 of the side pieces 2 and 1, respectively. A cross bar 10 similar to bar 7 is fixedly secured in the side pieces closely adjacent the uppermost rod 9 and in contact therewith. The rod 9, together with the bars 7 and 10, provide a corrugated rubbing surface the individual elements of which are effectually secured against movement longitudinally of the board. A cross brace 11 which is secured to the legs 3 and 4, and a top piece 12 secured in the upper ends of the side pieces by tenon joints, coöperate with the bars 7 and 10 to effectually prevent lateral movement or spreading apart of the side pieces of the board.

A back board 13 is mounted in close contact with one face of the rubbing portion of the board composed of the rods 9 and bars 7 and 10. This back is of such width as to fit snugly between the side pieces 1 and 2, and of such length as to extend to within a short distance above the lower rod 7. The upper portion of the back board is beveled upwardly and inwardly, on its outer face, as at 13^a so as to provide a portion which can be readily inserted into a longitudinally extending groove 14 formed in the under face of top board 12 for this purpose. The inner edge of this groove is in the plane of the surface of the rubbing portion of the board against which the back board fits. A soap shelf 15 is secured to the inner face of the back board 13. The under face of this shelf is inclined, as at 15^a, and the shelf is so positioned that, when the back board is in operative position, the under face of the shelf will rest on the uppermost portion of bar 10 so as to prevent downward movement of the back board, the top board 12 and the soap shelf thus coöperating to positively prevent movement of the back in either direction longitudinally of the board. This back board is secured in position by a clamping bar 16 which is pivotally secured at its center to the board 13. The ends of bar 16 are beveled outwardly and are adapted to fit snugly into the shelf grooves 17 and 18 formed in the inner faces of side pieces 1 and 2, respectively, when the arm is turned into horizontal position thus securing the back firmly in position. By this means, the back may be readily removed for

washing the underfaces of the rod 9 and bar 10, and may be as quickly and easily replaced.

As will be noted from Figs. 4 and 5 of the drawing, the side piece 1 is provided with two of the grooves 17, which are positioned equi-distant from the central groove 6, and side piece 2 is provided with two grooves 18 which are in alinement transversely of the board with the grooves 17. The top piece 12 is also provided with two longitudinally extending grooves 14 which are positioned equi-distant from the center of the top piece. By this construction, the board may be quickly and easily secured at either side of the rubbing portion thereof preferred, as will be evident. This renders it possible, when one surface of the rubbing portion of the board has become worn, to quickly and easily shift the board so as to expose the other surface, thus materially increasing the life of the board and its usefulness.

As will be noted, the rubbing portion of the board is composed mainly of the rods 9 which are all of identical construction, and the side pieces 1 and 2 are identical, the bars 7 and 10 being duplicates of each other. All of these parts may be quickly and easily produced at small cost, thus providing a board of very simple construction which may be made very cheaply.

What I claim is:—

1. In wash boards, two spaced side pieces each provided in its inner face with a central longitudinally extending groove and two lateral grooves parallel with and equi-distant from said central groove, a plurality of rods mounted in the central grooves in superposed relation, brace bars secured in said side pieces above and below said rods so

as to prevent movement of the same longitudinally of the board, a back board positioned between the side pieces closely adjacent the said rods, a top board secured to the upper ends of the side pieces, a soap shelf secured on the inner face of the back board and so positioned as to coöperate with the top board and the upper brace bar so as to prevent longitudinal movement of the back board, and means carried by the back board and adapted to engage into said lateral grooves for securing the back board in operative position adjacent either rubbing surface formed by the said rods, optionally.

2. In wash boards, two side pieces each provided in its inner face with a central longitudinally extending groove and two lateral grooves parallel therewith and equi-distant from the central groove, a plurality of rods mounted in said central groove in superposed relation, brace bars secured in said side pieces above and below said rods so as to prevent movement of the same longitudinally of the board, a back board positioned between the side pieces closely adjacent the said rods, and a clamping bar pivotally secured at its center on the said back board and having its ends beveled so as to be engageable into the said lateral grooves of the side pieces whereby the back board may be secured in position adjacent either face of the rubbing element, optionally.

In testimony whereof I affix my signature in presence of two witnesses.

JOSIAH LEDAN.
